US0D1096608S

(12) **United States Design Patent** (10) **Patent No.:** **US D1,096,608 S**
(Xu et al.) (45) **Date of Patent:** **** Oct. 7, 2025**

(54) **BUTTON CELL**

(71) Applicant: **Zhuhai CosMX Battery Co., Ltd.**,
Guangdong (CN)

(72) Inventors: **Desheng Xu**, Zhuhai (CN); **Yongwang Wang**, Zhuhai (CN)

(73) Assignee: **Zhuhai CosMX Battery Co., Ltd.**,
Zhuhai (CN)

(**) Term: **15 Years**

(21) Appl. No.: **29/771,074**

(22) Filed: **Feb. 19, 2021**

(30) **Foreign Application Priority Data**

Jun. 29, 2020 (CN) 202030341475.3

(51) **LOC (15) Cl.** **13-02**
